ATTORNEY.

UNITED STATES PATENT OFFICE.

THOMAS E. CLARK, OF DETROIT, MICHIGAN, ASSIGNOR TO CONTINUOUS TRAIN CONTROL CORPORATION, OF DETROIT, MICHIGAN, A CORPORATION OF MICHIGAN.

CONDUCTOR FOR TRAIN-CONTROL SYSTEMS.

Application filed April 14, 1924. Serial No. 706,375.

This invention relates to the control of railway trains by means of radio-frequency currents carried by the rails in the manner set forth in my co-pending application, Serial Number 676,014, filed November 21, 1923; and its object is to obviate the difficulties arising by reason of the locomotive or other vehicle equipped with proper receiving mechanism passing over or becoming stationary within dead sections or blocks, such as those embodying railway crossings and those in which the track rails rest on steel viaducts or bridges.

When the properly equipped vehicle passes over or comes to rest in a dead section, no proper signal can be received from the rails, even if the track ahead is clear. My invention consists in a proper connection between the blocks on each side of such dead section so that the train controlling current may be the same on both sides of such dead section and be present in proper auxiliary conductors throughout such dead sections so that the locomotive or other controlled vehicle passing through or remaining over said section may receive proper train controlling impulses.

This invention may be embodied in railway tracks having such dead sections in the manner illustrated conventionally in the accompanying drawings, in which Fig. 1 is a diagrammatic plan of a railway crossing wherein the tracks are provided with my novel conductors. Figs. 2 to 8 inclusive are similar views of modified embodiments of this invention.

Similar reference characters refer to like parts throughout the several views.

In the train control system shown in my said pending application, a transformer is provided for supplying radio-frequency current, also called carrier current, to each block, and where the track is used for one way traffic, this transformer is connected to the departure end of the block. The rails are also used as the conductors of the usual current to operate or control the signal system and either this current or the carrier current energizes a relay at the entrance end of the block which relay controls the operation of the transformer of the next block in

the rear. If a block is occupied, the rails thereof are short-circuited and the relay controlling the next block in the rear is de-energized and "danger" conditions are set up in the transformer of the next block in the rear. "Danger" conditions in any block result in "caution" conditions in the next block thereto, toward the rear.

Where the tracks rest directly on the steel work of bridges or viaducts, or where railway crossings occur, the rails cannot be used as conductors of the signal and carrier currents so other means must be provided to carry these currents around such sections. The several figures of the drawings show such arrangements.

In Fig. 1, I have shown two railway tracks crossing each other, the crossing itself comprising the rails 1 to 12 inclusive. The rails 7 and 8 are in alignment with but insulated from the rails 13 and 14 respectively, while the rails 11 and 12 are in alignment with but insulated from the rails 15 and 16 respectively. The crossing comprising the rails 1 to 12 inclusive is a dead section and the ordinary signal currents are usually conducted around such sections by means of wires 17 and 18 (shown in dotted lines) connecting to the adjacent rails 13 and 14 on one side and 15 and 16 on the other. The ordinary track battery 19 connects to rails 15 and 16 in the usual manner. The signal instrumentalities are indicated as a unit by the letter B in Fig. 1, but form no part of the present invention.

As described in my said application, means are provided to impress radio-frequency or carrier currents upon the outer rails 15 and 16. While any desired means may be used for this purpose, I have conventionally indicated a generator 21, a transformer 22, a standard high-frequency generating tube 23, variable inductance 24, resistance 25, battery 26, condensers 27 and wires 28 and 29 connecting to the rails 15 and 16 respectively.

Conductors 32 and 33 are shown extending from the rails 15 and 16 to the rails 13 and 14 respectively. These conductors will usually be made much heavier than necessary to carry the signaling and carrier

currents in order to be safe from breakage and will extend parallel to the rails 7—9—11 and 8—10—12 respectively, on either side thereof, and will preferably be enclosed in

5 cases or trunkings 34 of wood so as to avoid breakage. A balancing condenser 35 may be found desirable between the rails 13 and 14.

10 The rails 13 and 14 and the conductors 32 and 33 are substantially extensions of the rails 15 and 16 respectively for all train signaling and control purposes and as trains enter this track from the left in Fig. 1, a strong induced field travels ahead of the first axle of the train and proper instrumentalities on the train respond thereto.

15 The wires 17 and 18 could be used to conduct the carrier currents and when present may carry them, but I prefer to install the heavy wires 32 and 33 even when wires 17 and 18 are present. The signal currents and the carrier currents do not affect each other.

20 The wires 17 and 18 are usually carried by poles at cross-overs a distance from the rails and under those conditions would not be practical as conductors of carrier currents which should be carried by conductors placed as near as possible to the rails so that the magnetic flux of the carrier currents will properly affect the collecting instrumentalities on the locomotives at the cross-over

25 points.

30 My experience has been that the high-frequency generators operate properly in circuit with the track batteries and track relays, the reason probably being that the internal resistances of the batteries and relays are many times that of the rails and conductors 32 and 33. I have found little difference in the carrier currents in the rails whether the batteries and relays were connected or not. Some carrier current probably flows through both track batteries and relays but the amount is of no consequence. In my former application, I have choke coils to prevent this flow but subsequent tests have shown that they may be omitted.

35 In the structures shown in Figs. 2 to 8 inclusive, the rails 41 and 42 of the dead sections are insulated electrically from the rails 43 and 44 on the entrance side and the rails 45 and 46 on the departure side. In each case transforming and transmitting instrumentalities A connect to the rails 45 and 46 respectively by means of the wires 47 and 48.

40 In Fig. 2, the rails 43 and 44 are again connected by a balancing condenser 49 but a condenser 50 is shown in each of the conductors 51 and 52 connecting the rails 45 and 46 to the rails 43 and 44 respectively. In this construction the wires 53 and 54 to carry the signal currents are retained as these currents cannot pass the condensers 50. But as a portion of the carrier current can also pass over these wires, when conditions are favorable, it may be found desirable to

50 insert the inductances or choke coils 55 in these conductors, as shown in Figs. 3 to 8 inclusive, to stop the radio-frequency current while permitting the track signal currents to pass. The balancing condenser may be omitted, if desired, but such a condenser is usually found desirable at the entrance end of each block to complete the circuit for the carrier current.

55 In Fig. 4, the wires 53 and 54 with their inductances 55 are the same as above described but the conductors 56 and 57 are provided with condensers 50 at each end. In certain exposed sections, such as tracks laid on metal bridges, there is danger of the conductors 53 and 54 becoming disturbed and grounded. Under such conditions the track signal circuit would also be grounded, but the passage of the track signal current over the conductors 53 and 54 to the point where the grounding occurs will be prevented by these condensers 50.

60 In Fig. 5, the conductors 58 and 59 connect to the rails 45 and 46 through condensers 50. At the opposite end of the dead section, the rails 43 and 44 are connected by means of an adjustable inductance 60 and two condensers 50. The ends of the conductors 58 and 59 have sliding contact with this inductance to vary the amount of inductance between the conductors and the adjacent rails or track sections. The reason for this is that the length of the track sections, indicated by 43 and 44 in this figure, may vary greatly and with variation in length will be a variation in capacity. By making use of the variable and adjustable inductance the capacity is compensated for. The inductance has the effect of building up a current condition at the departure end of the block indicated by 43 and 44, and by varying this inductance the character of the carrier current for this block can be accurately adjusted to compensate for the variations in capacity of the block.

65 In Fig. 6 a loose coupled inductance consisting of the primary winding 61 connected to the conductors 62 and 63 and the secondary winding 64 connecting to the rails 43 and 44 through the condensers 50 is used for this same purpose of compensating for the variations in capacity of the block indicated by 43 and 44.

70 In Fig. 7, a loose coupled inductance connects the rails 45 and 46 to the conductors 66 and 67, and another such inductance connects these conductors to the rails 43 and 44. Each inductance consists of a primary winding 61 and a secondary winding 64. The closed oscillating circuit consisting of the rails 45 and 46, the winding 61 and condenser 50, the wires 47 and 48 and the transformer A, produce an induced current in the adjacent secondary winding 64 and therefore in the closed oscillating circuit

consisting of the conductors 66 and 67 and in the primary 61 at the opposite end of the conductors. This induced current produces a second induced current in the third closed 5 oscillating circuit consisting of the adjacent secondary winding 64, condenser 50 and track rails 43 and 44 which are again connected at their entrance end by a balancing condenser of the usual type.

10 In Fig. 8, a complete oscillating circuit of the full length of the block is provided. The circuit consists of two long sides, the transmitting mechanism A and the well known 15 balancing condenser at the entrance end of the block. The sides of the circuit bridge a dead section by means of the conductors 70 and 71 which connect to the rails at the ends of the dead section by means of the condensers 50 and adjustable inductances, 20 each comprising a primary winding 72 and a secondary winding 73. In such a construction, the carrier current is more liable to be uniform throughout the length of the block.

These examples of constructions for bypassing dead sections with train control currents such as is required in the system described in my co-pending application indicate that other modifications are possible and may be made by those skilled in the art 30 without departing from the spirit of my invention as set forth in the following claims.

I claim:—

1. In a train control system, in combination with a two-rail track divided into blocks insulated from each other, means to impress radio-frequency current on one of the blocks, conductors electrically connecting the rails of said block to the rails of a second 40 non-adjacent block in the direction from from which trains approach, and a condenser between the rails of said second block.

2. In a train control system, in combination with a two-rail track divided into blocks insulated from each other, one of said blocks constituting a dead section, means to impress radio-frequency current on the rails of one of the blocks, conductors electrically connecting the rails of said last named block 50 to those of another block on the opposite side of said dead section, and means embodying a condenser connecting the rails of said last named block.

3. In a train control system, a pair of 55 rails, means to impress radio-frequency current on said rails, a pair of conductors extending parallel to the rails and having ends connected to the rails adjacent the current supply, a balancing condenser in each conductor, and means to electrically connect the opposite ends of said conductors to said rails at a distance from the point of attachment of said current supply.

4. In a train control system, a pair of 65 rails, means to impress radio-frequency cur-

rent on said rails, a pair of conductors extending parallel to the rails and having ends connected to the rails adjacent the current supply, a balancing condenser in each conductor, and means to electrically connect the 70 opposite ends of said conductors to said rails at a distance from the point of attachment of said current supply comprising a variable coupler of which the primary coil connects to the conductors and the secondary 75 coil connects to the rails.

5. In a train control system, a pair of rails, means to impress radio-frequency current on said rails, a pair of conductors extending parallel to the rails and having ends 80 connected to the rails adjacent the current supply, a balancing condenser in each conductor, means to electrically connect the opposite ends of said conductors to said rails at a distance from the point of attachment 85 of said current supply comprising a variable coupler of which the primary winding connects to both conductors, and a pair of condensers connecting the ends of the secondary winding of the coupler to the rails. 90

6. In a train control system, a two-rail track divided into blocks insulated from each other, one of said blocks constituting a dead section, means to impress radio-frequency current on the rails of one of the blocks at one side of said dead section, and conductors electrically connected to the rails receiving said current and to the rails of a block on the other side of said dead section, said last named connection comprising a 100 variable inductance.

7. In a train control system, a two-rail track divided into blocks insulated from each other, one of said blocks constituting a dead section, means to impress radio-frequency current on the rails of one of the blocks at one side of said dead section, and conductors electrically connected to the rails receiving said current and to the rails of a block on the other side of said dead section, said last named connection comprising a 105 variable inductance and a pair of condensers.

8. In a train control system, a two-rail track divided into blocks insulated from each other, one of said blocks constituting a dead section, means to impress radio-frequency current on the rails of one of the blocks at one side of said dead section, conductors electrically connected to the rails receiving said current and to the rails of a block on the other side of said dead section, said last named connection comprising a variable inductance and a pair of condensers, and conductors for signaling current extending 115 around said dead section and connecting to the rails. 120

9. In a train control system, a two-rail track divided into blocks insulated from each other, one of said blocks constituting a dead 125

section, means to impress radio-frequency current on the rails of one of the blocks at one side of the dead section, and conductors for the radio frequency current electrically connected to the rails receiving said current adjacent to the points of connection of said current supply and extending substantially

parallel to the rails of said dead section to and electrically connected to the rails on the opposite side of said dead section and a condenser in each of said conductors to prevent the passage of direct currents. 10

THOMAS E. CLARK.
